STRAIGHT BAR KNITTING MACHINE

Ernest Start, Wilford, and Raymond Blood, Shepshed, England, assignors to William Cotton Limited, Loughborough, England

Application June 22, 1956, Serial No. 593,191

Claims priority, application Great Britain July 1, 1955

9 Claims. (Cl. 66—82)

This invention is for improvements in knitting machines for successively producing knitted blanks from the same yarn by the employment of means including a row of loop forming elements and one or more thread carriers traversable along said row, and having means for pressing off each blank so that one or more lengths of yarn then extends or extend from the thread carrier or thread carriers to the pressed off blank.

In straight bar knitting machines and primarily underwear and outerwear machines or pant frames in which it is required to produce knitted blanks for garments such for example as ladies' jumpers or cardigans. When producing blanks for these garments it is required to commence with a length of fabric which is different from the remainder of the fabric. For this purpose our U. S. patent applications Serial Nos. 470,455 and 575,047 disclose arrangements in which a point bar having a separately-made run-on portion on it is applied to the machine during the knitting of one blank and in which means are operated to automatically transfer the separately-made run-on portion from the points to the needles at the commencement of knitting of the next blank, there being also provided auxiliary draw-off means for attachment to the separately-made run-on portion for initial draw-off and main draw-off means for subsequently substituting for the auxiliary draw-off means. This separately-made run-on portion may be a rib fabric portion but it is alternatively required to provide a straight bar knitting machine not only with means such that it is capable of producing a blank commencing with a rib fabric portion but also with means such that it is capable of alternatively commencing with a turned welt which is either in the form of a separately-made run-on portion or is produced on the machine. Such a machine is disclosed in our U. S. patent application Serial No. 635,167.

The displacement of the point bar from its inoperative position to the operation position includes a displacement from a forward location to the more rearward location of the needles, and it is effected a short time after the blank has been pressed-off. The pressing-off of the blank is immediately followed by rotation of a draw-off roller in the machine to further wind on to it that part of the blank extending from it, and this results in a length of yarn being drawn through the operative thread feeder so as to extend forwardly from the feeder to the blank on the draw-off roller. It will be appreciated that the blank on the roller, being in somewhat relaxed state, is of less width than when being produced and as a result of this the length of yarn extending from the feeder to the blank on the draw-off roller inclines from the feeder in a direction inwardly of the adjacent selvedge needles, and the disadvantage exists that when the point bar is displaced rearwardly to its operative position, the points are likely to foul the yarn in the region of the selvedge needle. As a result yarn breakage or mis-positioning of yarn may occur such that yarn

2

is not fed satisfactorily to those needles required to receive it for the initial course of each blank.

An object of the invention is to provide means in a knitting machine for the control of the aforesaid length or lengths of yarn such as to ensure satisfactory feeding of yarn to those needles required to receive it for the initial course of each blank.

The invention provides in a knitting machine for successively producing knitted blanks from the same yarn

10 by the employment of means including a row of loop forming elements and at least one thread carrier traversing to and fro along the row of loop forming elements, and means for pressing-off each blank so that a length of the yarn then extends from the thread carrier to the 15 pressed-off blank, yarn deflector means which is displaceable to deflect the yarn extending from the thread carrier and locate that part of it which is adjacent the loop forming elements in pre-determined attitude relative thereto. Preferably the predetermined attitude is substantially normal to a row of needles in the machine and also preferably such that the yarn extends between sinkers in the machine movable between successive needles. Conveniently the yarn deflector means comprises a hook fixed on a carrier member, the carrier 20 member being linearly displaceable in a direction parallel to the row of needles for engagement of the hook with the yarn and for the location of said part of the 25 yarn in the substantially normal attitude, and also being angularly displaceable transverse to said direction 30 for location of said part of the yarn in the attitude extending between the sinkers. There may be a rod constituting said carrier member, mounting means in which the rod is freely supported for sliding movement in said 35 direction parallel to the row of needles and for angular movement about its own major axis, and limit stop means on the rod and the mounting means limiting such movements. More specifically there is provided, mounted on a stationary frame part of the machine, spaced bearing brackets constituting the mounting means for the 40 rod, a guide bar and a graduated scale extending between the bearing brackets, a slidably adjustable stop on the guide bar co-operating with said scale, a stop fixed on the rod to move between one of the bearing brackets and the adjustable stop to adjustably limit the linear 45 displacement of the rod to variably measured distances, angularly spaced stops on the rod to co-operate with opposite sides of said frame part and limit the angular displacement of the rod, and a handle fixed on the rod for its displacement manually.

50 The invention also provides a machine as above, being a multi-section straight bar knitting machine in which there are a plurality of knitting sections and an intermediate non-knitting section, wherein said rod extends along the plurality of sections and has a plurality 55 of the hooks fixed thereon one in each knitting section, and further wherein said mounting means for the rod, the guide bar and scale, the various stops, and the handle are disposed in or in the region of said intermediate section.

60 The invention further provides a machine as above having a point bar displaceable to engage its points with the needles in the process of providing on the needles a length of knitting fabric constituting the commencement of each blank, and wherein the predetermined attitude of said part of the yarn is such as to be clear 65 of the path of said points when they are being thus displaced.

In a machine as above there may be provided employing a plurality of thread carriers the succession of blanks or each succession of blanks such that after pressing off each blank there are a plurality of lengths of yarn extending from the thread carriers to the present-off blank,

and having one of said yarn deflector means for each length of yarn. In this modification the plurality of hooks are preferably mounted on the rod for simultaneous displacement.

More specifically in this modification there may be a cleat or the like at a side location to which the plurality of lengths of yarn are fastened so that they all extend in similarly inclined manner from the thread carriers to the cleat before the deflection of the yarns by the plurality of hooks.

In a further modification the machine as above, instead of employing the cleat or the like, is provided wherein after pressing off the blank, at least two of the plurality of lengths of yarn extend at relatively different inclinations from the thread carriers to the pressed off blank, and having at least two of said yarn deflector means, one for each of the differently inclined lengths of yarn, and which means are separably displaceable in the relatively different manner necessary because of the different inclinations of the two lengths of yarn.

In a further modification the machine as above, instead of employing the cleat or the like, is provided wherein after pressing off the blank, the plurality of lengths of yarn extend in convergent manner from the thread carriers to the pressed off blank, and wherein for deflecting at least the outermost lengths of yarn outwardly there are provided a pair of said rods displaceable in opposite linear directions and each having at least one of the hooks fixed thereon for the respective lengths of yarn.

The above and other features of the invention set out in the appended claims are incorporated in the construction which will now be described, as a specific embodiment with reference to the accompanying drawings in which:

Figure 1 is a diagrammatic plan view of a multisection straight bar knitting machine according to the invention.

Figure 2 is an enlarged plan view including one complete knitting section of said machine.

Figure 3 is a cross sectional view of Figure 2.

Figure 4 is a detail perspective view of a yarn control device according to the invention.

Figure 5 is a plan view illustrating a modified arrangement.

Figure 6 is a plan view illustrating said modified arrangement at a later stage of operations.

Figure 7 is a plan view illustrating a further modified arrangement.

Referring now to Figure 1 a Cottons patent underwear and outerwear straight bar knitting machine, or pant frame of multi-section type is provided with means for forming knitted blanks constituting body parts KB of garments successively in each knitting section KS (such as front and rear body parts or sleeve body parts), draw-off rollers 1 (Figures 2 and 3), draw-off hooks, and means for pressing-off the body parts KB when formed. There are also provided in the machine (Figure 3) mounting means 2 for point bars 3 substantially as described in the said specification of our U. S. patent application Serial No. 575,047, said mounting means 2 being adapted to have point bars 3 removably fitted to them in inoperative position and having lengths of rib fabric RF on the points 4 thereof (which are conveniently of right-angular form), and the mounting means 2 being automatically displaceable by means according to said specification for advancing the point bars 3 to operative position in co-operation with the needles N in the respective knitting sections KS (Figure 1) when required.

More specifically at any suitable time during the production of the body parts KB, point bars 3 each of which has a length of rib fabric RF run-on to its points 4, are fitted into the mounting means 2, one bar 3 to each mounting means in each knitting section KS of the machine. When the body parts KB have been completely

formed they are pressed-off and the draw-off rollers 1 are further rotated to complete winding of the body parts on to them. This results (as exemplified in Figure 2) in lengths of yarn Y being drawn through the operative thread carriers 5 so as to extend from the thread carriers 5 in a manner inclining inwardly from the adjacent selvedge needles at position SNP to the contracted body parts KB on the draw-off rollers 1.

There is provided in the machine a yarn control device 10 (as shown in Figure 4) for controlling said lengths of yarn. More specifically the device comprises a rod 6 (Figure 1) which extends substantially the whole length of the machine in suitable spaced bearing brackets 7 fixed to the template rail 8 of the machine. These brackets 7 are located at the top rear edge 8a of the template rail 8 (Figure 3) so that the rod 6 is disposed slightly to the rear of this top edge 8a of the template rail 8. The rod 6 is slidably disposed in the bearing brackets 7 and it has fixed on it a plurality of hooks 9 (Figure 1) one for each knitting section KS of the machine. Each hook 9 normally projects in rearwardly and downwardly inclined manner (Figure 3) from the rear of the rod 6 and at a location to the outer side of said length of yarn (Figures 2 and 3) in its knitting section KS (i. e. as shown in full lines in Figures 2 and 3, to the outer side of the yarn length Y shown in broken lines with respect to the adjacent selvedge needle at position SNP) and with its mouth 9a directed outwardly. The hooks 9 are conveniently made of wire, and they may be mounted adjustably by screw means at position 10 (Figure 2) on the rod 6 for initial setting if desired.

To effect displacement of the rod 6 and hooks 9 there is provided a radially disposed hand grip 11 (Figure 1) on the rod 6 conveniently in a central non-knitting section NKS of the machine (if the machine is in accordance with said U. S. specification Serial No. 635,167) and stops are provided limiting both linear displacement of the rod 6 and angular displacement thereof about its axis. More specifically the bearing bracket 7' (Figure 4) forms a stationary stop 13 and the bearing bracket 7' is connected to the next bearing bracket 7" by a guide bar 14 and a graduated scale 15. Slidably mounted in the guide bar 14 there is an adjustable stop 16 which co-operates with the scale 15. The hand grip 11 has a boss forming one stop 17 on the rod 6 and this boss is formed with angularly spaced stops 17 and 18 (Figure 3). When the hooks 9 are disposed in said downwardly and rearwardly inclined position (Figure 3) at the outer side of the lengths of yarn Y (Figure 2) the hand grip 11 is disposed with stop part 12 thereof in abutting relationship (as shown in full lines in Figure 2) with one side of the adjustable stop 16 which prevents further movement of the hooks 9 outwardly, and the angular stop 17 (Figure 3) engages with the rear edge 8a of the template rail 8, which prevents further movement of the hooks 9 downwardly.

In operation of the yarn control device the hand grip 11 is first moved from the last mentioned position in a direction axially of the rod 6 away from the said adjustable stop to slide the rod 6 axially until the stop 17 engages the stop 13 of the bearing bracket 7'; this results in the hooks 9 being carried by the rod 6 from the outer side positions to positions disposed at the inner sides of the lengths of yarn Y (as shown in broken lines in Figure 2). Next the hand grip 11 is angularly displaced upwardly about the axis of the rod 6 (as shown in broken lines in Figures 2 and 4) to turn the rod 6 about its axis until the angular stop 18 engages the top of the template rail 8 (Figure 2); this results in the hooks 9 being angularly displaced by the rod 6 about the latter's axis upwardly whereby the mouths 9a of the hooks 9 are directed towards the lengths of yarn Y. Next the hand grip 11 is moved to slide the rod 6 in the reverse direction axially of the rod 6 back into engagement with the adjustable stop 16 thereby causing the hooks 9 to

engage the lengths of yarn Y and deflect them outwardly until those parts YP of the yarn extending between the hooks 9 and the thread carriers 5 are disposed substantially normal to the row of needles. Finally the hand grip 11 is angularly displaced rearwardly and downwardly back to its initial position whereat its angular stop 17 engages the rear edge 8a of the template rail 8, and this results in the hooks 9 being angularly displaced by the rod 6 about the latter's axis downwardly such as to deflect the lengths of yarn Y downwardly at the locations of the hooks 9 so that said part of each length of the yarn extending from its thread carrier 5 extends in downwardly inclined manner between adjacent sinkers immediately in front of its thread carrier.

The next operation is for the mounting of the point bars 3 to be automatically displaced towards the needles N until the points 4 co-operate with the needles N such that ensuing operation of the needles N causes transference of the lengths of rib fabric RF from the point bars 3 to the needles N after which knitting resumes in the formation of further body parts KB.

It will be appreciated that the fact of deflecting said lengths of yarn Y in the manner referred to ensures that the lengths of yarn Y are completely clear of the points 4 when they are advanced to co-operate with the needles N thereby ensuring satisfactory transference of the lengths of rib fabric RF from the point bars 3 to the needles N, and in consequence ensuring satisfactory feeding of yarn to those needles required to receive it for the initial course of the body part by which the latter is joined to the rib fabric.

In a modified arrangement wherein the body parts KB are made for example of Intarsia fabric or plated pattern fabric, the machine employs a plurality of thread carriers in each knitting section for forming each succession of the body parts such that after pressing off each body part there are a plurality of lengths of yarn extending from the thread carriers to each pressed-off body part. In one such arrangement, illustrated in Figure 5, in each knitting section the lengths of yarn are fastened to a cleat 19 at a side location so that they then extend in similarly inclined manner from the thread carriers 20 to 28 to the cleat. For controlling these lengths of yarn there is provided one of said hooks 9 for each length of yarn (the hooks being here indicated by the references 29 to 37). These hooks 29 to 37 are mounted on the rod 6 so that operation of the latter as before described results in all the lengths of yarn being simultaneously deflected each in the manner before described with reference to the one length of yarn (see Figure 6).

In a modification of this arrangement, the pattern of the fabric is such that when a body part in each knitting section is pressed off, the lengths of yarn extending from the thread carriers to the body part are disposed at relatively different inclinations as shown in Figure 7. For controlling these lengths of yarn two series of the hooks 9 (here indicated by the references 38 to 42 and 43 to 46) and two of the rods 6 (here indicated by the references 47 and 48) are provided, the hooks 38 to 42 being fixed on the rod 47 and the hooks 43 to 46 being fixed on the rod 48, and the mouths of the hooks of the two series being outwardly directed. Means such as the aforesaid bearing brackets, guide bar and scale, the various stops, and the handle, are provided for each rod 47, 48 thereby the rods may be separably operable in opposite linear directions. The hooks 38 to 42 are disposed on the rod 47 in such positions as to engage with those yarns which required to be deflected towards one side, whilst the hooks 43 to 46 are disposed on the rod 48 for engaging with those yarns required to be deflected to the other side. Consequently when the rods 47 and 48 are operated substantially in the manner as described with reference to the rod 6, with the exception of the rods 47 and

48 being displaced in opposite linear directions, all the yarns are deflected each substantially in the manner before described with reference to the one length of yarn.

In certain instances certain of the lengths of yarn may not require deflection and in such instances no hook or hooks is or are provided therefor.

What we claim is:

1. In a knitting machine for successively producing knitted blanks from the same yarn by the employment of means including a row of needles, at least one thread carrier traversing to and fro along the row of needles, and means for pressing-off each blank so that a length of the yarn extends from the thread carrier to the pressed-off blank, yarn deflector means comprising a hook fixed on a carrier member, the carrier member being linearly displaceable in a direction parallel to the row of needles for engagement of the hook with the yarn extending from the thread carrier and to deflect the yarn and locate that part of it which is adjacent the row of needles into an attitude extending substantially normal to the row of needles, and also being angularly displaceable transverse to said direction to deflect said yarn and locate that part of it into an attitude extending between the sinkers.
2. A machine as claimed in claim 1 being a multi-section straight bar knitting machine in which there are a plurality of knitting sections and an intermediate non-knitting section; having a rod constituting said carrier member and extending along the plurality of sections and having a plurality of hooks fixed thereon one in each knitting section; mounting means comprising spaced bearing brackets on a stationary frame part of the machine and in which the rod is freely supported for sliding movement in said direction parallel to the row of needles and for angular movement about its own major axis; a guide bar and a graduated scale extending between the bearing brackets; limit stop means limiting said movement and comprising a slidably adjustable stop on the guide bar cooperating with said scale, a stop fixed on the rod to move between one of the bearing brackets and the adjustable stop to adjustably limit the linear displacement of the rod to variably measured distances, and angularly spaced on the rod to cooperate with opposite sides of said frame part and limit the angular displacement of the rod; a handle fixed on the rod for its displacement manually; and said mounting means for the rod, the guide bar and scale, the various stops, and the handle, being disposed in the region of said intermediate section.
3. A machine as claimed in claim 1 having a point bar displaceable to engage its points with the needles in the process of providing on the needles a length of knitting fabric constituting the commencement of each blank, and wherein the deflected attitude of said part of the yarn is such as to be clear of the path of said points when they are being thus displaced.
4. A machine as claimed in claim 1 having a rod constituting said carrier member, mounting means in which the rod is freely supported for sliding movement in said direction parallel to the row of needles and for angular movement about its own major axis, and limit stop means on the rod and the mounting means limiting such movements.
5. A machine as claimed in claim 4 having, mounted on a stationary frame part of the machine, spaced bearing brackets constituting the mounting means for the rod, a guide bar and a graduated scale extending between the bearing brackets, a slidably adjustable stop on the guide bar co-operating with said scale, a stop fixed on the rod to move between one of the bearing brackets and the adjustable stop to adjustably limit the linear displacement of the rod to variably measured distances, angularly spaced stops on the rod to co-operate with opposite sides of said frame part and limit

the angular displacement of the rod, and a handle fixed on the rod for its displacement manually.

6. A machine as claimed in claim 4 employing a plurality of thread carriers for the blanks such that after pressing off each blank there are a plurality of lengths of yarn extending from the thread carriers to the pressed-off blank, and having one of said yarn deflector means for each length of yarn comprising a plurality of hooks mounted on the rod for simultaneous displacement.

7. A machine as claimed in claim 6 having a cleat or the like at a side location to which the plurality of lengths of yarn are fastened so that they all extend in similarly inclined manner from the thread carriers to the cleat, before the deflection of the yarns by the plurality of hooks.

8. A machine as claimed in claim 6, wherein after pressing off the blank, at least two of the plurality of lengths of yarn extend at relatively different inclinations

5

10

15

from the thread carriers to the pressed off blank, and having at least two of said yarn deflector means, one for each of the differently inclined lengths of yarn, and which means are separably displaceable in the relatively different manner necessary because of the different inclinations of the two lengths of yarn.

9. A machine as claimed in claim 6, wherein after pressing off the blank, the plurality of lengths of yarn extend in convergent manner from the thread carriers to the pressed off blank, and wherein for deflecting at least the outermost lengths of yarn outwardly there are provided a pair of said rods displaceable in opposite linear directions and each having at least one of the hooks fixed thereon for the respective lengths of yarn.
